US0D1011835S

(12) **United States Design Patent** (10) **Patent No.:** **US D1,011,835 S**
(45) **Date of Patent:** **** Jan. 23, 2024**

(54) **CONDIMENT BOTTLE**

(71) Applicant: **Helen of Troy Limited**, St. Michael (BB)

(72) Inventor: **Lance E. Hazelton**, Maplewood, NJ (US)

(73) Assignee: **Helen of Troy Limited**, St. Michael (BB)

(**) Term: **15 Years**

(21) Appl. No.: **29/812,026**

(22) Filed: **Oct. 19, 2021**

(51) **LOC (14) Cl.** **07-01**

(52) **U.S. Cl.**

USPC **D7/510**; D9/446

(57) **CLAIM**

The ornamental design for a condiment bottle, as shown and described.

DESCRIPTION

FIG. 1 is a perspective view of a condiment bottle showing my new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

The broken lines in the drawings depict portions of the condiment bottle that form no part of the claimed design.

1 Claim, 6 Drawing Sheets
